(57) **CLAIM**

The ornamental design for a headband with bow, as shown and described.

DESCRIPTION

FIG. 1 is a top, left, front perspective view of a headband with bow according to a first embodiment of my new design; FIG. 2 is a front elevation view of the first embodiment of the headband with bow;

FIG. 3 is a left side elevation view of the first embodiment of the headband with bow, the right side elevation view being a mirror image of FIG. 3;

FIG. 4 is a rear elevation view of the first embodiment of the headband with bow;

FIG. 5 is a top plan view of the first embodiment of the headband with bow, the bottom plan view being a mirror image of FIG. 5;

FIG. 6 is a top, left, front perspective view of a headband with bow according to a second embodiment of my new design;

FIG. 7 is a front elevation view of the second embodiment of the headband with bow;

FIG. 8 is a left side elevation view of the second embodiment of the headband with bow, the right side elevation view being a mirror image of FIG. 8;

FIG. 9 is a rear elevation view of the second embodiment of the headband with bow; and,

FIG. 10 is a top plan view of the second embodiment of the headband with bow, the bottom plan view being a mirror image of FIG. 10.

The broken lines depict portions of the headband with bow that form no part of the claimed design.

1 Claim, 4 Drawing Sheets
